ARTICLE OF JEWELRY

Aaron Reiter, New York, N. Y.

Application June 13, 1941, Serial No. 397,840

11 Claims. (Cl. 63—15)

This invention relates to the art of jewelry and more especially to finger rings.

One of the objects of the invention is to provide an article of jewelry such as, for example, a finger ring or bracelet with ornamental parts carried thereby and relatively movable thereon from a position in which said parts overlap to a position in which the parts are separated sufficiently to expose the overlapped area of one of said parts. For example, when the ornamental parts are in the form of simulated hands normally disposed in clasping relation, at least one of said hands is movable out of said clasping relation so that an inscription normally concealed by said movable hand-simulating part can be exposed to view for observation thereof, and in this connection an important feature of the invention resides in providing a construction whereby the parts are relatively movable circumferentially of the annular member of the ring or bracelet while on the wearer's finger or wrist as the case may be so that it is unnecessary to remove the ring from the finger in order to observe said normally concealed inscription.

Another object of the invention is to provide the annular member and the relatively movable part with interengaging means for holding the movable part in proper position on the annular member and for guiding said movable part to and from its operative position in association with the companion part.

A further object of the invention is to provide the hand-simulating part with means for releasably holding them in clasping relation.

A yet further object of the invention is generally to provide an improved article of the character described.

In the drawing:

Fig. 1 is a top view of a ring embodying the present invention showing the relatively movable ornamental parts in normally engaged relation;

Fig. 2 is a top plan view, on a larger scale, showing the ornamental parts disengaged from each other to expose an inscription on the upper surface of one of said parts;

Fig. 3 is a view in elevation of one side of the ring;

Fig. 4 is a view in elevation of the other side of the ring;

Fig. 5 is a sectional view, on a larger scale, on the line 5—5 of Fig. 3;

Fig. 6 is a sectional view on the line 6—6 of Fig. 4;

Fig. 7 is a sectional view on the line 7—7 of Fig. 4;

Figs. 8 and 9 are views in elevation looking in the direction of lines 8—8 and 9—9 of Fig. 4. Referring now more particularly to the drawing, the article of jewelry here shown as a finger ring 10 comprises a peripherally continuous annular member 12 forming the shank of the ring and relatively movable parts 14 and 16 here shown as simulated hands carried by said annular member at the portion thereof which is normally uppermost when the finger ring is on the wearer's finger. As here shown said parts 14 and 16 are in the form of simulated hands, hand part 14 being disposed with the palm uppermost while hand part 16 is disposed with the back of the hand uppermost, said hand parts being disposed in hand-clasping relation in the normal position of said parts illustrated in Figs. 1, 4, 8 and 9. Thus, as shown, said parts 14 and 16 have portions which extend radially beyond the outer periphery of annular member 12. Hand part 16 is intended to carry an inscription indicated at 18 in Fig. 2, said inscription being normally concealed by the overlapping portions of hand-simulating part 14 when the latter is in clasping relation with hand-simulating part 16, but as illustrated in Fig. 2 part 14 is movable to a retracted position sufficient to uncover the inscription 18 so that the latter can be observed, and by virtue of the construction presently to be described the movement of part 14 can take place while the ring is on the wearer's finger. It will be noted that the circumferential extent of parts 14 and 16 is less than the periphery of the annular member 12.

As here shown hand-simulating part 16 is in fixed relation to annular member 12, while hand-simulating part 14 is movable circumferentially of annular member 12, although it will be understood that this relation can be reversed so that part 14 is in fixed relation while part 16 is movable. Hand simulating part 14 has an end portion 20 thereof which engages the outer peripheral surface of annular member 12 and which has opposite end portions 22 and 24 which slidably engage the opposite side edges 26 and 28, respectively, of said annular member. A peripherally extending slot 30 is provided in annular member 12, and part 20 is provided with an inwardly extending portion 32 in integral or fixed relation therewith and projecting through slot 30 in slideable engagement with the opposite walls thereof for guiding part 14 in its movement toward and away from companion part 16. Part 32 terminates in an enlargement 34 which engages the inner surface of annular member 12 for holding part 14 in position on annular member 12 and

for preventing substantial movement of said part radially of said annular member. Enlargement 34 is preferably sufficiently wide so that the opposite side edges thereof slidably engage the adjacent side edges 36 in the grooved portion 38 formed in the upper part of the annular member. Thus part 14 is guided for movement circumferentially of annular member 12 by portions 22, 24, 32 and 34 of said part in engagement with the adjacent portions, respectively, of said annular member, the movement of said part 14 to the normally projected portion and to the retracted position illustrated in Figs. 1 and 2, respectively, being limited by the length of slot 30. The annular member is also provided with a slot 30a in the part thereof adjacent the fixed part 16, for the purpose of symmetry of design, and it will be understood that said slot 30a can be omitted. It will also be understood that, if desired, part 16 can be movable on annular member 12 whether or not part 14 is movable thereon as just described, in which case the mounting of part 16 can be the same as the mounting of part 14. In other words, either or both parts 14 and 16 can be movable, although the arrangement described above wherein part 16 is stationary and part 14 is movable is preferred.

Hand-simulating parts 14 and 16 are provided with interengaging means for releasably securing the same in overlapping, simulated hand-clasping relation, illustrated in Figs. 1, 4, 8 and 9. For this purpose part 14 is provided with a dot projection 40 which is releasably received with a snap action in a small recess 42 provided in the thumb portion 44 of part 16, and it will be noted that when the parts are in clasped relation thumb portion 44 of part 16 overlies part 14 near the thumb portion 46 thereof. The portion 48 of part 16 near the wrist portion of the latter is raised somewhat above the palm portion, while the outer ends of the finger portions of part 14 are curved downwardly to engage the raised portion 48 when the two hand parts are in clasping relation whereby said parts are held firmly but releasably together.

While I have shown and described the preferred embodiment of my invention it will be understood that the latter may be embodied otherwise than as herein specifically shown or described, and that in the illustrated embodiment certain changes in the details of construction and in the arrangement of parts may be made. Further, while the invention has been illustrated and specifically described in reference to a finger ring, it will be understood that said invention can be applied to other articles, especially bracelets. Also, it will be understood that the relatively movable parts carried by the annular member can be formed otherwise than as hand-simulating parts. As these and other changes and adaptations may be made and will occur to skilled artisans in view of the present disclosure, I do not wish to be limited to the construction herein shown or described except to the extent which may be required by the scope of the appended claims.

Having thus described my invention, what I claim and desire to secure by Letters Patent is:

1. An article of jewelry such as a ring, bracelet or the like comprising an annular member, relatively movable parts carried by said annular member externally to and adjacent the outer periphery thereof, one of said parts being movable on said outer periphery of the annular member in a direction circumferentially of said

annular member toward and away from said other part while said annular member is in position on the wearer, said movable part having a circumferential extent less than that of said annular member.

5 2. An article of jewelry such as a ring, bracelet or the like comprising an annular member, relatively movable parts carried by said annular member externally to and adjacent the outer periphery thereof, one of said parts being movable on said outer periphery of the annular member in a direction circumferentially of said annular member toward and away from said other part while said annular member is in position on the wearer, said movable part having a circumferential extent less than that of said annular member, and interengaging means on said parts for holding them releasably in engagement with each other.

20 3. An article of jewelry such as a ring, bracelet or the like comprising an annular member, relatively movable parts carried by said annular member and having portions disposed externally of the outer periphery of said annular member radially of the latter, one of said parts being movable in a direction circumferentially of said annular member toward and away from said other part while said annular member is in position on the wearer, said portions being in overlapping relation in one of their relative positions, said one of the relatively movable parts and said annular member having interengaging portions for guiding said last mentioned part for said movement on the annular member circumferentially thereof toward and away from said other part.

30 4. An article of jewelry such as a ring, bracelet or the like comprising an annular member, relatively movable parts carried by said annular member, both of said parts having portions disposed radially outwardly of the outer periphery of said annular member, one of said parts being movable in a direction circumferentially of said annular member toward and away from said other part, said parts being relatively movable from one position in which said portions are in overlapping relation to another position in which said portions are in spaced relation in a direction circumferentially of said annular member.

45 5. An article of jewelry such as a ring, bracelet or the like comprising an annular member, relatively movable parts carried by said annular member, both of said parts having portions disposed radially outwardly of the outer periphery of said annular member, one of said parts being movable on said outer periphery of the annular member in a direction circumferentially of said annular member toward and away from said other part, said parts being relatively movable from one position in which said portions are in overlapping relation to another position in which said portions are in spaced relation in a direction circumferentially of said annular member, said one of the relatively movable parts and said annular member having interengaging portions for guiding said last mentioned part for said movement on the annular member circumferentially thereof toward and away from said other part.

60 6. An article of jewelry such as a ring, bracelet or the like comprising an annular member, relatively movable parts carried by said annular member and having portions disposed externally of the outer periphery thereof, one of said parts

being movable in a direction circumferentially of said annular member toward and away from said other part, said parts being relatively movable from one position in which said portions are in overlapping relation to another position in which said portions are in spaced relation in a direction circumferentially of said annular member, and interengaging means on said parts for holding them releasably in engagement with each other in said overlapping relation.

7. An article of jewelry such as a ring, bracelet or the like comprising an annular member, a part carried by said annular member in fixed relation thereto and having a portion disposed externally of said annular member in a radial sense, and a part slidable on said annular member circumferentially thereof and having a portion disposed externally of said annular member and movable toward and away from said portion of said fixed part.

8. An article of jewelry such as a ring, bracelet or the like comprising an annular member, a first part carried by said annular member and having a portion disposed externally of the outer periphery thereof in a radial sense, and a second part slidable on said annular member circumferentially thereof toward and away from said said first part, said second part having a portion disposed externally of said annular member in a radial sense, said annular member having a circumferentially extending slot and said second

part having a portion projecting into said slot and guided thereby.

9. An article of jewelry such as a ring, bracelet or the like comprising an annular member, relatively movable parts carried by said annular member, one of said parts being slidable on said annular member circumferentially thereof toward and away from said other part, said one of the parts having portions thereof slidably engaging the outer and inner peripheral surfaces, respectively, of said annular member.

10. An article of jewelry such as a ring, bracelet or the like comprising an annular member, relatively movable parts carried by said annular member and having portions extending radially beyond the outer periphery of said annular member one of said portions being slidable on said annular member circumferentially thereof toward and away from said portion of the other part.

11. An article of jewelry such as a ring, bracelet or the like comprising an annular member, a part carried by said annular member in fixed relation, a part slidable on said annular member circumferentially thereof toward and away from said fixed part, said movable part having portions thereof slidably engaging the outer and inner peripheral surfaces, respectively, of said annular member and opposite side portions thereof slidably engaging the opposite side edges, respectively, of said annular member.
